UNITED STATES PATENT OFFICE

WILLIAM J. LYNCH, OF BUFFALO, NEW YORK

SPRAYING DEVICE

Application filed November 26, 1929. Serial No. 409,951.

This invention relates to a nozzle or spray device which is adapted to be supplied with fluid under pressure and to eject the same in the form of either a mist or a spray, such as is required in dishwashing machines, shower baths, cement and paint guns, milk can cleaners, etc.

The object of the invention is to provide a device of this character which permits of optionally obtaining either a divergent, convergent or straight spray, and also permits of conveniently flushing out the device whenever sufficient dirt or gummy sediment has accumulated as to cause the spray to be irregular in shape or insufficient in pressure.

Another object of the invention is to provide a spray device of such character that a plurality of the same may be actuated simultaneously by means of a single control lever.

In the accompanying drawings:

Figure 1 is a side elevation of the spray device of the type used to spray water in a dishwashing machine, the same being illustrated as coupled in the piping of a fluid pressure line, shown fragmentarily.

Figure 2 is a horizontal medial section thereof, taken on line 2-2 Fig. 1.

Figures 3 and 4 are vertical transverse sections, taken on correspondingly numbered lines of Fig. 1.

Figure 5 is a fragmentary section on a reduced scale of a plurality of the spray devices and actuated by one common control lever.

Similar characters of reference indicate like parts in each of the several figures of the drawings.

The numeral 10 represents a hollow body or spray casing whose interior is tubularly connected to the pipes 11 and 12 by means of tapered gas pipe threads 13 or the like and is preferably prevented from any displacement relatively thereto by means of the headless set screws 14. The said pipes 11 and 12 are tubularly connected with a suitable source 45 of water or other fluid, which is under pres-

sure, said pressure being obtained by any suitable means, for example by the use of a centrifugal pump (not shown).

The central lower part of the said casing 10 is depressed to form the cylindrical spray chamber 15 which is formed by the cylindrical side casing wall 16 and the lower flat horizontal casing wall 17. Disposed within said casing and in axial vertical alignment with the said spray chamber 15 is a spray sleeve 18 whose lower end is enlarged to form the annular spray head 20 which is adapted to be received within an annular hole or spray aperture 21 formed co-axially in the aforesaid lower casing wall 17, the diameter of said aperture being somewhat larger than the diameter of said spray head 20. The latter is suitably bored axially to receive a guide pin 22 whose upper end is threaded into the internally screw threaded bore of 65 an adjustable thimble or stop bushing 23. The latter is provided with external screw threads 23 which thread into suitable internal screw threads formed in a vertical annular flange 24 which is preferably formed 70 integral with and projects axially and upwardly from the main spray casing 10.

Said spray sleeve 18 with its spray head 20 is adapted to be moved up or down (inwardly or outwardly) upon said guide pin 22. To 75 prevent any dash pot effect or the possibility of excessive dirt or sediment accumulating in the lower part of the bore of said spray sleeve, a suitable drainage hole 25 is bored diametrically through the lower part of said 80 sleeve. The upward movement of said sleeve is limited by its coming into contact with the lower face of the aforesaid stop bushing 23. The latter may be adjustably screwed up 85 or down in the main spray casing 10 and the upward movement of the spray sleeve 18 thereby adjustably limited, the properly adjusted position of said bushing being rendered thereafter immovable by means of a lock nut 26 which is threaded onto the external 90

threads of said adjusting bushing 23 and is adapted to bear against the upper face of the annular flange 24 of the main casing. It is desirable to have as much of the aforesaid guide pin 22 project into said spray sleeve 18 as possible without having the lower end of said guide pin come into contact at any time with the bottom of the bore of said spray sleeve. This result is obtained by screwing said guide pin 22 up or down in the aforesaid bushing 23 to the desired position and then locking said guide pin in place by means of a set screw 27. This adjustment is not affected by the vertical adjusting movement of the adjusting bushing 23 itself, relatively to the main casing 10, inasmuch as the guide pin 22 and said adjusting bushing 23, in this case, move up or down as a unit.

When the spray head 20 is in its central position with reference to the spray aperture 21 (as shown in full lines in the drawings) the fluid under pressure in the chamber 10 is forced to flow downwardly between said spray head and said spray aperture and issue therefrom in a powerful concentrated stream or spray of hollow cylindrical or tubular form, this being the type of spray particularly desired when a forcible action of the spray is needed, as in washing milk bottles, milk cans or ice cream cans, or in washing a person's hair when in a shower bath, etc. When the spray head 20 is in its upper position (see upper dotted lines 20a, Fig. 3) the stream or spray of fluid under pressure converges as it issues from the spray device, and this brings the opposite sides of the conical sheet of the fluid into violent contact with each other and causing, as a result of this impact, a finely divided mist or fine spray, such as is particularly desired in the spraying of cement and paint, in air conditioning, and in the less vigorous employment of the shower bath, etc. On the other hand, if the spray head 20 is moved downwardly from its central position the spray is caused to diverge or flare out as it issues from the spray device and is thereby enabled to forcibly cover a large area, this being the condition particularly desired in dish washing, in the ordinary use of shower baths, etc. In practically all cases where a spray is required, all three of these sprays are useful to some extent at least and even where, in certain installations, any one or two of the sprays are not customarily needed, the construction whereby all three of the sprays may be obtained, when desired, has two distinct advantages.

The construction of the device may be made inexpensive by reason of its standardized construction which is applicable to a wide variety of uses.

Any dirt or sediment which may accumulate in any one position of the spray head may be quickly and thoroughly flushed out by

moving the said head up and down to the other positions of the head.

When the spray head is in its extreme upper or extreme lower position and thereby a converging or diverging spray produced respectively, the sheet of fluid which issues as a spray, is prevented from undue dispersion by the beveling at 30 and 31 of the outer edges of the upper and lower faces respectively of the spray head 20. These bevels also reduce the "wire drawing" of the fluid.

The upper end of the spray sleeve 18 is provided with upper and lower actuating flanges 32 and 33 between which is arranged the outer enlarged portions of the arms of a fork lever 34, the movement of which effects the up or down movement of said spray sleeve 18 and its enlarged spray head 20. The downward movement of said spray head 20 is adjustably limited by an adjusting stop screw 70 which is threaded vertically through

the wall of the main casing 10 and is adapted to bear with its upper end against the adjacent lower face of the forked lever 34. The outer or enlarged end of said fork lever is secured rigidly by any suitable means, for instance by a taper pin 35 and set screw 36 to an operating or control shaft 37 which passes completely through a suitable longitudinal enlargement 38 of the main casing 10 and is disposed parallel to the fluid pipes 11 and 12.

Accessibility to said taper pin 35 (see Fig. 3) is effected by providing upper and lower plug screws 40 and 41 which pass through the casing walls, and accessibility to the set screw 36 is effected by providing a plug screw 42 which also passes through the walls of said main casing. End shifting of the control shaft is prevented by a pair of anti-shifting or limiting collars 43 which bear with their inner faces against the opposite sides of the hub of the fork lever 34. The bores of said collars are arranged to rotatably receive the control shaft 37 and their peripheral faces are provided with external screw threads which engage with suitable internal screw threads 44 formed in the walls of the spray casing enlargement 38 coaxially with the control shaft 37. One of the limiting collars 43 may, if desired, be cast integrally with the main spray casing 10. Screw slots 45 are preferably provided on the outer faces of said limiting collars to facilitate their adjustment, and the collars are held firmly in their adjusted position by means of set screws 46 (Fig. 2). Leakage of the fluid at this point is prevented by the employment of soft packing washers or rings

47 which encircle the control shaft and are pressed against the outer faces of the said limiting collars 43 by means of packing glands 48. The latter are provided on their peripheries with external screw threads which also engage with the aforesaid inter-

nal screw threads 44 of the spray casing 10. The outer end faces of each of said packing glands 48 is provided with a pair of screw slots 50 of X or cross shaped form. Each of said packing glands is held firmly in its adjusted position by means of a set screw 51. The turning of the control shaft 37 is effected by any suitable means, for instance by a manual control lever 52 mounted on the 10 projecting end of said shaft and secured thereto by a set screw 53. At the opposite end of the spray casing 10 and also mounted upon the control shaft 37 is a retaining arm 54, the central part thereof being bored to 15 receive said shaft and the lower part being split longitudinally in a plane extending through the axis of said shaft to form the clamping ears 55. These ears are adapted to be pressed together firmly by a clamping 20 screw 56 which passes through the one ear and is preferably threaded into the other ear in the usual and well-known manner, and is locked in place by a lock nut 57. In a similar manner, a detention plate or 25 retaining abutment 58 is secured to the fluid pipe 12, said abutment being provided with semi-spherical depressions 60 and 61 which are adapted to receive the adjacent face of an upper ball detent 62, whenever the spray 30 head 20 is in its extreme upper or lower position respectively. The abutment 58 is also provided with a lower semi-spherical depression 63 which is adapted to receive the front face of a lower ball detent 64. The ball 35 detents 62 and 64 are preferably restrained from coming out entirely from their pockets in the retaining arm 54 by peening over the corners of the latter at 59 in the usual and well known manner. These ball detents 40 are resiliently pressed toward the abutment plate by compression springs 65 and 66 respectively, the pressure of the latter being suitably regulated by headless adjusting screws 67 and 68 respectively. The reason 45 for using a pair of ball detents instead of only one is because if only one were used, the three depressions required would overlap each other and an adequate dividing wall of metal separating the one from the other would 50 not be obtained. As it is, each semi-spherical depression is isolated and each is thereby enabled to hold its companion ball detent in a firm though resilient manner.

Any desired number of spray devices as 55 shown in Fig. 5 may be strung along the pipes 11 and 12 and all of the same actuated by the one common control lever 52. In such case only one retaining abutment 58 and its companion retaining arm 54 and detents 62 and 63 are required for all of the spray devices. Where the spray devices do not lie 60 in one straight line, a number of control shafts may be operatively connected together by means of chains, bevel gears, linkages or other suitable means, and in this case also,

only one retaining abutment and its companion retaining arm and detents are required. One example of such an arrangement is shown in Fig. 5 in which the fluid pipe 12 is tubularly connected by a pipe L to a lateral fluid pipe 120 and the primary control shaft 37 is coupled up with a secondary control shaft 370 through the medium of the bevel gears 71 and 72, both of said shafts being actuated by the one control lever 52. As 70 will also be noticed in Fig. 5, only one abutment 58 and one retaining arm 54 (with its companion detents) is required to hold both shafts 37 and 370 in any of the three operating positions desired, i. e. to produce either 75 a diverging, converging or straight spray of the fluid.

For the installation and operation of just one spray device, the same is connected up with the fluid pressure pipe line 11 and 12 80 and locked thereto by set screws 14; then the guide pin 22 is screwed down as far as possible without having its lower end come into contact with the bottom of the bore of the spray sleeve 18 at the time when the latter is 85 pushed up against the lower end of the stop bushing 23. The set screw 27 is then tightened. The stop bushing 18 is now moved up or down, so that when the spray sleeve is positioned tight up against the lower face of 90 said stop bushing (effected by a suitable movement of the manual control handle 52) the converging misty spray produced is of the desired shape and fineness. The locknut 26 is then tightened. The adjustment as to both 95 shape and intensity of the diverging shape of the spray is effected by moving up or down the adjusting stop screw 70 which limits the downward movement of the forked lever 34 and hence the retaining abutment 58 is now 100 clamped onto the fluid pipe 12 in such position as to have their semi-spherical depressions 60, 61 and 63 at the proper distances from the control shaft 37. Then the retaining arm 54 is clamped to said control 105 shaft with just a small clearance between it and said retaining abutment 58 and in such circumferential position that the upper ball detent 62 enters the depressions 60 and 61 when the control lever is moved to its extreme 110 positions. The resilient pressure against said ball detents is now regulated by turning the adjusting screws 67 and 68 either in or out, as may be desired. The shape of the straight spray produced by the spray 115 head when in its central position is not effected by any relatively slight up or down movements of said spray head, and therefore no provision is made or needed for adjusting this shape of spray, the engagement of the lower ball detent 64 with its depression 63 being sufficiently accurate for this purpose. To prevent endwise shifting of the control 120 shaft the position of the limiting collars 43 is now properly adjusted and then the pack- 125

ing glands 48 screwed in until a suitable water-tight joint of the soft packing rings 47 is effected.

It is obvious that the details of construction may be varied considerably without departing from the spirit of the invention, the particular type of spraying device illustrated being only one embodiment of the invention as relating more particularly to dish washing machines of the type shown in my Patent No. 1,440,612, issued Jan. 2, 1923.

I claim as my invention:

- 15 1. A spraying device comprising a casing supplied by fluid under pressure and having an aperture; a spray head axially movable in said aperture so as to be positioned either centrally, outwardly or inwardly; and adjustable stops to limit the extreme outward and inward movements of said head.
- 20 2. A spraying device comprising a casing supplied by fluid under pressure and having an aperture; a spray head axially movable in said aperture so as to be positioned either centrally, outwardly or inwardly; adjustable stops to limit the extreme outward and inward positions of said head; and means for holding said head in either its central, inward or outward position.

In testimony whereof I hereby affix my

30 signature.

WILLIAM J. LYNCH.
